UNITED STATES PATENT OFFICE.

JOSEPH E. MULLAN, OF PHILADELPHIA, PENNSYLVANIA, ASSIGNOR TO BAYUK CIGARS INCORPORATED, OF PHILADELPHIA, PENNSYLVANIA, A CORPORATION OF MARYLAND.

CIGAR-BUNCH MACHINE.

Application filed February 7, 1925. Serial No. 7,487.

My invention relates to cigar bunch machines of the automatic type and more particularly to an improved mechanism for applying paste to the filler binder.

- 5 Heretofore cigar bunch machines of the automatic type have been provided with mechanism for applying paste to the filler binder after it has been placed on the rolling apron. Such mechanism as has been 10 heretofore in use has proved substantially satisfactory, but is open to objection as over-complicated and difficult of adjustment. Further, such mechanism is objectionable in that in its construction no provision is made 15 for rendering it inoperative with the result that if the continuity of production is interrupted paste is smeared on the rolling apron and where any interference with the paster arm occurs breakage results.
- 20 Now it is the object of my invention to provide a paster of novel construction which will be efficient and accurate in operation and further to provide a paster which may be thrown out of operation independently of the 25 operation of the bunch machine as a whole and which will automatically go out of action on the meeting of any obstruction.

Having now indicated, in a general way, the nature and purpose of my invention, I 30 will proceed to a detailed description thereof with reference to the accompanying drawings, in which I have illustrated a preferred embodiment, and in which—

Fig. 1 is a side elevation, partly in section, of a portion of a cigar bunch machine provided with a paster embodying my invention.

Fig. 2 is a detail view showing a paster guide cam.

Fig. 3 is a plan view of a bunch rolling table and paster.

Fig. 4 is a rear view of the paster showing method of mounting.

Fig. 5 is a plan view of the paster wheel showing adjustable mounting on the paster arm.

a represents the frame of a cigar bunch machine upon which is mounted a rolling table *b* on which is operated in the usual manner a rolling apron. Mounted in suitable bearings in the frame is a cam shaft *c* driven through gearing *d* and carrying a cam *e*, having a cam surface formed on its side, and a pulley *f*.

65 The frame is apertured, as at *g*, for the

passage of a curved lever *h* pivotally mounted as at *i* and provided at its lower end with a cam follower wheel *j*. A spring *k* attached to the frame and to the lever *h* above pivot *i* tends to hold the cam follower 60 against the cam surface formed on cam *e*, so that as cam *e* revolves the lever will be oscillated on its pivot.

Removably secured to the frame adjacent the aperture *g* is a bracket *l* upon one side of which is mounted a receptacle *m* adapted to hold a supply of paste, in which a wheel *n*, mounted on a shaft *o* journaled in the side walls of the receptacle, is adapted to dip. A pulley *p* is mounted on one end of shaft *o* and receives a belt *q* which passes around pulley *f* on cam shaft *c*, so that as the cam shaft revolves the wheel *n* is revolved in the paste supply. An idler pulley *r* is provided for the belt.

To the upper end of lever *h* is connected, by means of a slot and pin connection, one end of a paster arm *s*, the other end of which receives the threaded end of a stem *t* upon the free end of which is revolubly 80 mounted a paster wheel *u*, the periphery of which is channelled and milled as shown in Fig. 5. The stem *t* is secured in adjusted position by means of a lock nut *v*.

Mounted on the side of the paster arm *s* 85 intermediate its ends is a roller *w* adapted to follow a guide cam *x* mounted on bracket *l*. The guide cam, as shown in Fig. 2, presents from its rear to its front an upwardly slanting surface *x'* with a drop-off at the forward end onto a lower surface *x''* which extends on a substantial level to join the surface *x'* below its forward end. The front portion *y* of the surface *x'* is made separate and pivotally mounted as at *y'* in order to permit the roller *w* to lift it against the tension of a spring, indicated at 3, and pass from the lower surface *x''* to the surface *x'*, as clearly shown in Fig. 2. Beneath the forward end of surface *x'* is positioned a 90 pivotally mounted buffer *z*, the free end of which is yieldingly maintained beneath the end of surface *x'* for the reception of the roller *w* by means of a spring 2. When the roller reaches the end of cam surface *x'*, it turns on its pivot under the weight of the arm and passes the roller down to the buffer *z*, which, under the weight of the paster arm, is depressed against its spring and serves to 95 permit the roller down easily on the cam surface 100 as clearly shown in Fig. 2. When the roller reaches the end of cam surface *x'*, it turns on its pivot under the weight of the arm and passes the roller down to the buffer *z*, which, under the weight of the paster arm, is depressed against its spring and serves to 105 permit the roller down easily on the cam surface 110 as clearly shown in Fig. 2.

x'' . The spring 3 returns the forward portion y into line with the cam surface x' when the roller clears it.

In operation, assuming the cam shaft c to be rotating, the wheel n will be rotated in the paste and the lever h will be oscillated about its pivot by cam e . Assuming now that the lever h is in its rearward position, as indicated in dotted lines, Fig. 1, the paster arm will be retracted and lowered so that the paster wheel will be in contact with and receive a supply of paste from the wheel n and the roller w on the paster arm will be at the rear of guide cam x . As the lever h is moved forward by cam e , the paster arm will move forward and be raised by the cam surface x' , until the roller w reaches the forward end of surface x' at which time the paster wheel w will be above the rolling table b , at a point desirably located in reference to a binder previously placed on the table by the usual transfer device. As the roller w leaves the cam surface x' and is let down to surface x'' , as shown in Fig. 1, the end of the paster arm and the paster wheel is dropped into contact with the binder on the rolling table. At this point, the lever h will have reached its forward position. On movement of the lever h toward the rear, the paster arm is retracted and the roller w following the cam surface x'' permits the paster wheel to roll over the desired portion of the binder and apply paste. As the roller w approaches the rear of cam surface x'' , it contacts with the underside of the pivoted portion y of the surface x' and lifts it to clear a path to surface x' , as indicated in Fig. 2, down which the roller travels permitting the end of the paster arm to lower until the paster wheel w again contacts with wheel n .

It will be observed that in the device embodying my invention the paster may be thrown out of operation by merely drawing lever h and cam follower j away from cam e against the action of spring k . This may be accomplished manually by simply holding the paster arm in retracted position or by means of a suitably located lever to which is connected one end of a cable 4, the other end of which is connected to lever h . As shown in Fig. 1, if the cable be led to a point not substantially behind lever h , there is provided a conduit 5 through which the cable passes and which serves as a guide and prevents undue wear on the cable. It will be noted that should the paster arm or other part of the mechanism meet with an obstruction, such obstruction would only need to be sufficient to overcome the tension of spring k to automatically throw the mechanism out of operation without possibility of damage.

It will be further observed that in accordance with my invention the paster can be assembled and applied as a unit and pro-

tection is made for readily adjusting the paster wheel either through adjustment of the bracket l or adjustment of the paster wheel through adjustment of stem t or through adjustment of both.

Having now fully described my invention, what I claim and desire to protect by Letters Patent is:

1. A paster for cigar bunch machines comprising, in combination, a paste-applying member, means to reciprocate said member, and means to raise and lower said member during its reciprocation.

2. A paster for cigar bunch machines comprising, in combination, a paster arm, a paste-applying member carried by said arm, means adapted to reciprocate said arm in a horizontal plane, and means adapted to cause said arm to oscillate in a vertical plane during its reciprocation.

3. A paster for cigar bunch machines comprising, in combination, a paste-applying member, a support for said member, means adapted to reciprocate said support, a guide cam, and means carried by said support adapted to follow said cam.

4. A paster for cigar bunch machines comprising, in combination, a paste-applying member, a support for said member, means adapted to reciprocate said support, a guide cam, and means carried by said support adapted to follow said guide cam whereby, in the movements of reciprocation of said support, said paste-applying member will be alternately raised and lowered.

5. A paster for cigar bunch machines comprising, in combination, a paste-applying member, mechanism for the actuation of said member, a cam for actuating said mechanism, and means yieldingly retaining said mechanism in operative relation with said cam.

6. A paster for cigar bunch machines comprising, in combination, a pivoted lever, a cam, a cam follower carried by said lever, means to yieldingly maintain said cam follower in contact with said cam, a paster arm connected to said lever, a paster wheel carried by said arm, a guide cam, and a cam follower carried by said arm and adapted to follow said guide cam.

7. A paster for cigar bunch machines comprising, in combination, a pivoted lever, a cam, a cam follower secured to said lever adjacent one of its ends, paste-applying mechanism secured to said lever adjacent its other end, and means yieldingly retaining said cam follower in operative relation with said cam.

8. A paster for cigar bunch machines comprising, in combination, a pivoted lever, a cam adapted to oscillate said lever, a cam follower secured to said lever adjacent one of its ends, means yieldingly retaining said cam follower in operative relation with said

cam, an arm pivoted to said lever adjacent its other end and adapted to be reciprocated by said lever, a paster wheel carried by said arm, a guide cam adjacent said arm and a cam follower carried by said arm and adapted to follow said guide cam, said guide cam being formed to raise and lower said arm in its movements of reciprocation.

9. A paster for cigar bunch machines comprising, in combination, a pivoted lever, a cam adapted to oscillate said lever, a paster arm pivotally connected to said lever and adapted to be reciprocated thereby, an inclined cam surface having a section adjacent its upper end pivoted, a second cam surface beneath said pivoted section and merging at one end with said first mentioned surface, and a cam follower carried by said arm and adapted in the reciprocation thereof to follow said cam surfaces.

10. A paster for cigar bunch machines comprising, in combination, a pivoted lever, a cam adapted to oscillate said lever, a paster arm pivotally connected to said lever and adapted to be reciprocated thereby, an inclined cam surface having a section adjacent its upper end pivoted, means adapted to normally maintain said section in line with said cam surface, a second cam surface beneath said section and adapted to receive a cam follower from the upper end of said first mentioned surface and merging at one end into said first mentioned surface, a support, means tending normally to maintain said support adjacent the upper end of said first mentioned cam surface and adapted to yield to effect the transfer of a cam follower from said first surface to said second surface, and a cam follower on said arm adapted to follow said cam surfaces, said means adapted normally to maintain said pivoted section in line with said first mentioned cam surface being adapted to yield to permit displacement of said section for the passage of the cam follower from said second cam surface to said first cam surface.

11. A paster for cigar bunch machines comprising, in combination, a pivoted lever, means to oscillate the lever, a paster arm se-

cured adjacent one end and adapted to be reciprocated by said lever, a stem extending laterally from said arm adjacent its free end, a revolute paster wheel mounted on said stem, a guide cam, and a cam follower mounted on said arm intermediate its ends and adapted to follow said guide cam in the movements of reciprocation of said arm.

12. A paster for cigar bunch machines comprising, in combination with a rolling table, a frame, a lever pivotally mounted on said frame, means to oscillate said lever, a paster arm secured at one end to said lever and adapted to be reciprocated thereby, a paster wheel mounted on said arm, a bracket mounted on said frame adjacent said lever, a paste receptacle removably mounted on said bracket, a revolute roll mounted in said paste receptacle, a cam mounted on said bracket, a cam follower carried by said arm intermediate its ends and adapted to follow said cam, said cam being adapted to oscillate said paster arm from said revolute roll to said rolling table to effect the reception of paste and the application of paste by said paster wheel.

13. A paster for cigar bunch machines comprising, in combination, a paste-applying member, mechanism for the actuation of said member, a cam for actuating said mechanism, means yieldingly retaining said mechanism in operative relation with said cam, and means for rendering said yielding means inoperative.

14. A paster for cigar bunch machines comprising, in combination, a pivoted lever, a cam, a cam follower secured to said lever adjacent one of its ends, paste-applying mechanism secured to said lever adjacent its other end, means yieldingly retaining said cam follower in operative relation with said cam, and means for withdrawing and maintaining said cam follower out of operative relation with said cam.

In testimony of which invention, I have hereunto set my hand, at Philadelphia, Pennsylvania, on this 21st day of January, 1925.

JOSEPH E. MULLAN.
